(57) **CLAIM**

The ornamental design for a control panel, as shown and described.

DESCRIPTION

FIG. 1 is a top front perspective view of a control panel showing my new design;

FIG. 2 is a front view thereof;

FIG. 3 is a top view thereof;

FIG. 4 is a first end view thereof; and,

FIG. 5 is a second end view thereof.

The back and bottom views are omitted from the drawing disclosure of the control panel as being devoid of surface ornamentation and not a part of the claimed control panel design.

The broken lines in the figures show unclaimed subject matter and form no part of the claimed design.
